PORTABLE TOILET TANK

James M. Kulka, 1623 S. Jefferson St., Chicago, Ill.

Filed Sept. 22, 1961, Ser. No. 66,804

Term of patent 14 years

(Cl. D4—5)

Fig. 1.

Fig. 2.

Fig. 3.

I claim:

The ornamental design for a portable toilet tank, substantially as shown and described.
